UNITED STATES PATENT OFFICE.

VICTOR RAISIN, OF PARIS, FRANCE, ASSIGNOR TO LA CIE. INDUSTRIELLE DES ALCOOLS
DE L'ARDÈCHE, OF PARIS, FRANCE.

SACCHARIFYING APPARATUS.

1,018,778.

Specification of Letters Patent. Patented Feb. 27, 1912.

Application filed March 16, 1909. Serial No. 483,812.

To all whom it may concern:

Be it known that I, VICTOR RAISIN, a citizen of the Republic of France, and resident of Paris, France, have invented a new and useful Saccharifying Apparatus, which apparatus is fully set forth in the following specification.

This invention relates to an apparatus intended to transform the whole or portion of the woody substance into sugar which is susceptible to fermentation, and other utilizable products. To that end, wood, as sawdust, or in any other form, and whatever be its nature, is treated with an acid particularly sulfurous acid, at a suitable temperature and pressure. The arrangement and proportions adopted for the apparatus for the treatment, insure the regularity and the rapidity of the reaction.

20 The apparatus in question is illustrated in the accompanying drawings, in which—

Figure 1 is a longitudinal vertical section, partly in side-elevation, and Fig. 2 an end-elevation, with an end-plate removed.

25 This apparatus comprises a cylindrical chamber *a* in which the mixing of the wood and the acid takes place. This chamber is constituted by a drum *b* having two tube-sheets *c*, *c'* secured thereto. A number of 30 mild steel tubes *d*, set in and connecting the two tube-sheets *c*, *c'* pass through the said chamber.

The interior of the apparatus may or may not be provided with a protective lining of 35 lead or other acid-resisting material.

At each end of the cylindrical chamber *a* is arranged an end-sheet *c*, *c'*, forming end-chambers *e* and *e'* communicating with each other through the tubes *d* and insuring 40 when steam is introduced into the end-chambers the uniform heating of the cylindrical chamber *a* to a suitable temperature for the treatment. As will be explained, the apparatus is rotated without the heating 45 being interrupted and the tubes *d* present a surface against which the wood contacts, so that a perfect and uniform transmission of heat to the wood is effected. An inlet steam-

pipe *h* passing through an opening in the center of the end-sheet *c* introduces live 50 steam into the end-chamber *e*. A packing-box *k* is provided to prevent the escape of steam around the pipe *h*. A baffle-plate *k'* spreads the steam from the pipe *h* to cause an even distribution of the same and to prevent 55 excessive impingement of the steam on the tube-sheet *c'*. An exhaust-pipe *m* passing through a similar opening and packing-box at the center of the end-sheet *c'* is provided with a radial bend *m*² and a circumferential bend *m*³ at the inner end *m*⁴, whereby the exhaust steam may escape or whereby the water of condensation may be forced out by the pressure of the steam.

The apparatus is provided at the end-edge 65 of the drum *b* with annular tracks *i*, *i'* and is supported by the said tracks upon two sets of four rollers *j* journaled in balance-beams *j*² balanced in U-shaped recesses in the top of standards *j*³. The driving is effected by a toothed rack *h*, carried by the drum *b* adjacent one track *i* (see Fig. 1), and a toothed pinion *g* mounted on the spindle *f* journaled in the standards *j*², *j*³ and carrying fast and loose pulleys *f*⁴, *f*⁵ or any 70 other suitable transmission means.

The apparatus is balanced so that its rotation should be uniform without any shocks to the transmission gear.

75 A manhole *p* having a suitable closable lid *p*² is provided in the side of the drum *b* emptying the contents of the drum after the treatment is effected.

The heating can be effected in any other suitable manner, steam being quoted for the 80 sake of example.

Having thus described my invention, I claim as new and desire to secure by Letters Patent:

In a saccharifying apparatus, the combination of an air-tight drum comprising a sheet-metal cylinder and tube-sheets, curved end-sheets forming end-chambers with said tube-sheets and each having a central opening, a plurality of tubes passing transversely through said drum and connecting 85 90 95

said end-chambers, steam inlet and outlet pipes passing respectively through the center openings of the end-sheets, a stuffing box for each pipe, a manhole and manhole-cover at the circumference of the drum, a baffle-plate at the inner end of the steam inlet-pipe, and means for rotating said drum.

In testimony whereof I have signed this specification in the presence of two subscribing witnesses.

VICTOR RAISIN.
